Specification of Letters Patent. Patented July 25, 1922.

Application filed November 14, 1921. Serial No. 515,057.

To all whom it may concern:

Be it known that we, JOHN ALBERT COLE and LEO JOSEPH SHORTER, both subjects of the King of England, residing at 5 Coventry, in the county of Warwick, England, have invented certain new and useful Improvements in Pistons, of which the following is a specification.

With internal combustion engines used on 10 motor vehicles, it is very desirable that the piston should remain always in contact with one side of the cylinder, as otherwise noise and "slap" occur as the contact of the piston changes from one wall of the cylinder to the 15 other, when the connecting rod passes beyond the dead centre.

Many suggestions have been made to ensure this permanent contact with one wall of the cylinder. In most cases the pistons are 20 slit or provided with springs, and it is the object of the present invention to provide a simple means, applicable if necessary to existing pistons, whereby contact can always be maintained with the same wall of the 25 cylinder.

According to this invention, the crown of the piston is flat and slopes from one side to the other so as to be out of perpendicular to the wall of the cylinder, that is, its plane 30 is oblique to the axis of the cylinder. Thus, when pressure occurs upon the top of the crown of the piston there is a small lateral component of thrust forcing it towards the desired cylinder wall, and this lateral thrust 35 prevents the piston leaving that wall as the connecting rod passes the dead centre.

The accompanying sectional drawing shows a piston A with the top B of the crown sloping at a slight angle from right 40 to left so that the piston always keeps in contact with the cylinder wall C.

In an internal combustion engine having a light weight piston of 80 millimetres bore, we have found that the desired result is obtained if one side of the piston is from two 45 to five millimetres higher than the other side. We do not, however, wish to limit the invention to these dimensions. We have also found that good results can be obtained by maintaining the thrust either on the wall with 50 which the piston normally is in contact during the compression stroke, or on that with which it normally would be in contact on the firing stroke. We prefer the contact to 55 be with the latter wall, but this again is not essential.

With this arrangement, apart from obviating noise or "slap," greater efficiency can be obtained because the resultant force due to the angularity of the crown of the piston 60 can be caused to re-act during the explosion stroke against the thrust imposed upon the cylinder wall due to the angularity of the connecting rod.

We are aware that in two-stroke engines 65 the crown of the piston has been sloped in such manner as to form a baffle thereon, but the object of this has been to attain a scavenging effect and not, so far as we are aware, to produce a side thrust upon the wall of the 70 cylinder, which is the object of our invention.

By this invention a very simple means is provided for maintaining permanent contact between the piston and one wall of the 75 cylinder, and the means can, if desired, be applied to existing pistons.

The foregoing advantages will be very evident in the case of internal combustion engines, because the working pressures are 80 considerably higher than in steam engines, and the application of the invention is therefore restricted to four-cycle internal combustion engines, because the maximum pressures are usually higher in these than in two-stroke 85 engines, and to the irreversible kind thereof because, if reversal were possible, the conditions improved in one direction of rotation, 90 would be rendered worse than before, during rotation in the opposite direction.

What we claim as our invention, and desire to secure by Letters Patent of the United States is:—

A piston for an internal combustion engine in which the whole of the crown of the 95 piston is flat and the plane thereof is oblique to the axis of the cylinder, the piston having a wrist pin bearing cutting the piston axis; the direction of slope of the crown being such that the edge thereof nearest the mouth 100 of the cylinder is against that side of the cylinder which takes the whole side thrust during the entire working stroke.

In testimony whereof we have signed our names to this specification in the presence of 105 two subscribing witnesses.

JOHN ALBERT COLE.
LEO JOSEPH SHORTER.
